UNITED STATES PATENT OFFICE

2,321,070

JOURNAL BOX

Joseph Dresner, St. Louis, Mo.

Application October 16, 1941, Serial No. 415,202

2 Claims. (Cl. 308—89)

This invention relates to certain new and useful improvements in journal boxes and, more particularly, to a bearing protector.

As is well known to substantially all railway hostlers and roundhouse mechanics, the journal box on railway car wheels is, at the present time, packed with absorbent cotton waste saturated with lubricant. The bearing surfaces of the journals proper, however, are formed of low-melting anti-friction alloys, such as babbitt and the like, and are, therefore, easily scored and damaged when subjected in localized areas to extensive friction and heat. For this reason, much difficulty has resulted from the tendency of the cotton waste to disintegrate, so that strands and isolated portions thereof are caught up by rotation of the axle and forcibly drawn between the bearing surface of the axle and the bearing surface of the journal. Frequently such strands of waste will become lodged between the bearing surfaces and, as a result of attendant friction, produce sufficient heat to score and damage the smooth bearing surface of the anti-friction alloy.

My invention hence has for its primary objects the provision of simple, efficient, and economical means for preventing cotton waste and other similar material from being drawn between the bearing surfaces of a car wheel axle and the journal.

It is a further object of my invention to provide means of the type stated which is simple and inexpensive, which may be readily and conveniently installed, which will not interfere with the normal operation of the bearing, which is rugged and durable, and which is otherwise highly convenient and satisfactory in the performance of its stated objects.

And with the above and other objects in view, my invention resides in the novel features of form, construction, arrangement, and combination of parts presently described and pointed out in the claims.

In the accompanying drawing,

Figure 1 is a perspective view of a journal bearing-member and protector constructed in accordance with and embodying my present invention;

Figure 2 is a fragmentary vertical sectional view of a journal box constructed in accordance with and embodying my present invention;

Figure 3 is a transverse sectional view of the journal box taken approximately along the line 3—3, Figure 2; and

Figure 4 is an inverted sectional view of the

journal box taken approximately along the line 4—4, Figure 3.

Referring now in more detail and by reference characters to the drawing, which illustrates a preferred embodiment of my invention, A designates a journal box of substantially conventional design having the usual plate or pad 1, which is machined on its under face with a transversely extending recess 2 for accommodating a complementarily shaped bronze bearing member 3. On its under face, the member 3 is provided with a lengthwise extending downwardly opening arcuate channel or recess 4 conventionally lined with a poured or otherwise suitably formed anti-friction bearing 5 for receiving a conventional car axle spindle or journal 6. It will, of course, be understood in this connection that the journal box A is of sufficient size to extend substantially below the car axle spindle 6 to provide a chamber c adapted for receiving a substantial quantity of lubricant saturated cotton waste w.

On each of its side faces adjacent one end, the bearing member 3 is provided with outwardly projecting bosses 7, and also on its side faces adjacent its forward end, the member 3 is cut away, as at 8, in the provision of laterally presented clearance faces 9. Loosely secured by means of bolts 10 upon, and depending from, each of the clearance faces 9, is a short hanger arm 11 formed of strap metal or other suitable material and rigidly mortised at its lower end in the outer vertical face of a substantially horizontal protector bar 12 formed preferably, though not necessarily, of molded fiber and extending lengthwise along the margin of the member 3 in downwardly spaced relation to the under face thereof. At its other end, the bar 12 is preferably enlarged in width in the provision of an offset end 13 for extending beneath the lug 7 and apertured for loosely accommodating a vertical stud 14 having an enlarged head 15 and being threaded at its upper end into the under face of the lug 7. Disposed encirclingly about the stud 14 in abutting engagement at its opposite ends 45 against the under face of the lug 7 and the upper face of the bar 12, is a compression spring 16 for normally urging the bar 12 downwardly against the head 15 of the stud 14.

On its inwardly presented vertical face, the protector bar 12 is preferably provided with a series of sawtooth-like serrations 17 for better enabling the respective protector bars 12 to catch and restrain the cotton waste which may be accidentally drawn up toward the bearing 5. In this connection, it should be noted that the length

of the hanger 11 and the length of the stud 14, taken together with the thickness and horizontal width of the protector bars 12, are such that the lower inwardly presented edges or corners of the serrations 17 will be positioned in close but non-touching proximity to the surface of the axle spindle 6, as best seen in Figure 2. It will, of course, be obvious that railroad cars move both in the forward and reverse directions and that the axle spindles likewise rotate in either direction, so that it is necessary to provide two identical and opposite protector bars 12 mounted on either side of the car spindle, as shown.

When in use, the protector bars 12 will effectively and efficiently catch and restrain the particles of cotton waste which tend to be drawn up against the surface of the bearing 5. The bearing-surface protectors of my invention are simple and inexpensive and may be readily installed in new journal-boxes or, with equal facility, installed in used journal-boxes which are being repaired in the roundhouse. In either case, it has been found that the protectors are rugged and durable and materially prolong the useful life of the bearing-surfaces with which they are associated.

It should be understood that changes and modifications in the form, construction, arrangement, and combination of the several parts of the journal box may be made and substituted for those herein shown and described without departing from the nature and principle of my invention.

Having thus described my invention, what I claim and desire to secure by Letters Patent is,

1. In combination, in a journal-box, a bearing-member for disposition upon a wheel-axle disposed within the box, the box having a chamber below such axle for receiving cotton waste and lubricant and said member being on a side face formed with an outwardly projecting boss at one end and cut-away in the provision of a clearance-space at its opposite end, a depending hanger-

arm loosely flatwise attached at an end to said member at said clearance-space, a longitudinal bar attached at one end to said arm and provided at its opposite end with an offset, and means including a stud engaging said bar at said offset and said member at said boss and a spring coiled on the stud intermediate the bar and said member for securing the bar at said opposite end yieldingly to the bearing-member in approximate parallel relation to the wheel-axle, the bar being provided on its inner face with a longitudinal series of serrations for catching and restraining from said member any cotton waste which may be drawn upwardly in the box on and by rotation of the wheel-axle.

2. In combination, in a journal-box, a bearing-member for disposition upon a wheel-axle disposed within the box, the box having a chamber below such axle for receiving cotton waste and lubricant and said member being on each of its opposite side faces formed with an outwardly projecting boss at one end and cut-away in the provision of a clearance-space at its opposite end, depending hanger-arms each loosely flatwise attached at an end to said member at a respective clearance-space, longitudinal bars each attached at one end to one of said arms and provided at its opposite end with an offset, and means for yieldingly retaining said arms at their said opposite end in spaced relation to said wheel-axle, said means including studs loosely engaging said bars at their respective opposite ends and said member at said bosses and springs coiled on said studs intermediate the under face of said bosses and said bars, and each of said bars being provided on its inner face with a longitudinal series of serrations for catching and restraining from said member any cotton waste which may be drawn upwardly in the box on and by rotation of the wheel-axle.

JOSEPH DRESNER.
